UNITED STATES PATENT OFFICE.

ALFRED BUNEL, OF NEW ROCHELLE, NEW YORK, ASSIGNOR TO THE E. S. HIGGINS CARPET COMPANY, OF NEW YORK, N. Y.

DESIGN FOR CARPET.

SPECIFICATION forming part of Design No. 29,804, dated December 13, 1898.

Application filed November 18, 1898. Serial No. 696,822. Term of patent 3½ years.

To all whom it may concern.

Be it known that I, ALFRED BUNEL, of New Rochelle, in the county of Westchester and State of New York, have invented and produced a new and original Design for a Carpet, of which the following is a specification, reference being had to the accompanying drawing, forming a part thereof, in which is shown a plan view of a piece of carpet embodying the features of my design.

The design consists of a central bouquet of flowers and foliage, the flowers being of the rose and daisy types, and smaller bouquets of similar flowers and foliage grouped around the main figure. 15

I claim—

The design for a carpet herein shown and described.

ALFRED BUNEL.
